UNITED STATES PATENT OFFICE.

ALFRED A. WOHLAUER, OF NEW YORK, N. Y.

LIGHTING-FIXTURE.

1,329,280.

Specification of Letters Patent. Patented Jan. 27, 1920.

Application filed May 24, 1918. Serial No. 236,357.

To all whom it may concern:

Be it known that I, ALFRED A. WOHLAUER, a native of the Kingdom of Germany, who have applied for citizenship in the United States, and am residing at New York, in the county and State of New York, have invented a certain new and useful Improvement in Lighting-Fixtures, of which the following is a specification.

10 My invention relates to the device described in my United States Letters Patent No. 1235951, issued August 7, 1917, and is designed as an improvement thereon. The shade holder therein described is designed 15 to be used for supporting a reflector and a globe ball or other shield for the source of light.

My present invention has for its object to simplify the construction of said device, and 20 to increase the efficiency of the lighting unit by forming one of the holding devices so as to cause it to form a baffle plate.

25 My means of accomplishing the foregoing objects may be more readily understood by having reference to the accompanying drawing, which is hereunto annexed and is a part of this specification, in which:

Figure 1 is a vertical sectional view of my improved device applied to a lighting unit 30 of the type to which it is applicable.

Fig. 2 is a fragmentary detail view showing the manner of assembling the structure.

Fig. 3 shows a modified form of construction.

35 Similar reference numerals refer to similar parts throughout the entire description.

As shown in the drawings, my invention comprises an upper and outer dust shield and ventilator 3, which is provided with a 40 central neck or stem 4, the walls of which are provided with threads 5, which are adapted to engage threads 6 formed on the neck 7, of the shade holder proper. This holder is provided with a flange 8, which 45 as shown, is in the shape of an inverted cone and terminates in a downwardly depending circumferential flange 9, which is adapted to engage a lip 10, formed on the ball or globe, which incloses the lighting unit.

50 A plurality of thumb screws 11, are provided to hold the globe 12 in position. The neck of the globe 12 is provided with a shoulder 13, which is adapted to receive an annular lip 14, formed around a central 55 opening of the reflector 15. In assembling the lighting unit, the reflector is first placed

on the globe 12, the annular lip 14, resting upon the shoulder 13, formed on the upper part of the globe 12. The depending flange is then placed over the lip 10, and the thumb screws 11, are tightened up in position. The shield and ventilator 3, is then screwed down upon the threads 6, until its lower edge engages the top wall of the reflector 15, as clearly seen in Fig. 1.

65 A plurality of openings 16, are formed on the neck or stem of the shade holder proper, for ventilating purposes and serve to carry away the heated air produced by the light source which is permitted to escape 70 through openings 14, formed in the shield and ventilator 3.

In Fig. 3, I have shown a modified form 75 of construction, in which I provide a supplemental plate 18, which is fitted to and coincides with the configuration of the baffle plate 8. This plate is preferably provided with an enamel which is baked on, thus affording a very satisfactory reflecting surface which noticeably increases the light re- 80 directed to the working plane.

Having described my invention, what I regard as new and desire to secure by Letters Patent of the United States, is:

1. A reflector and globe holder, comprising a ventilating cap, having a neck with threads formed thereon, a globe holder mounted in said neck, the lower portion of which is flanged outwardly forming a baffle plate of inverted conoidal shape, terminating in a downwardly depending flange, a secondary enamel baffle plate which is fitted to and coincides with the inverted conoidal flange, means mounted in said downwardly depending flange to hold a globe. 85

2. A reflector and globe holder, comprising a ventilating cap, having a neck with threads formed thereon, a globe holder, having a neck adapted to telescope the neck on the ventilating cap, there being threads on the neck of the globe holder which fit the threads in the neck of the ventilating cap, the lower portion of said globe holder being flanged outwardly forming a baffle plate of inverted conoidal shape, terminating in 100 a downwardly depending flange, a secondary enamel baffle plate which is fitted to and coincides with the inverted conoidal flange, means mounted in said downwardly depending flange to hold a globe. 105

3. A reflector and globe holder formed of an upper member, having a central cylin- 110

drical portion, with threads formed on the wall thereof, the lower portion of said cylinder being flanged outwardly forming a dust and ventilating guard, a globe holder 5 having a central cylindrical portion, having threads formed on the walls thereof, which are fitted to and coincide with the threads formed on the cylindrical portion of the dust and ventilating guard, the lower portion 10 of the cylindrical part of the globe holder being flanged outwardly forming a

baffle plate of inverted conoidal shape, which terminates in a downwardly depending flange, a globe having a reduced neck adapted to fit the inside of said downwardly depending flange, a shoulder on said globe, a reflector resting on said shoulder, and means mounted in the downwardly depending flange to engage the neck of the globe.

In testimony whereof I have signed the 20 foregoing specification.

ALFRED A. WOHLAUER.
